Inventor:

United States Patent Office.

JAMES R. CHILES, OF RICHMOND, VIRGINIA.

Letters Patent No. 73,782, dated January 28, 1868.

IMPROVED HEAD-REST FOR SEATS.

The Schedule referred to in these Letters Patent and making part of the same.

TO ALL WHOM IT MAY CONCERN:

Be it known that I, JAMES R. CHILES, of Richmond, in the county of Henrico, and State of Virginia, have invented a new and improved Head-Rest for Car and other Seats; and I do hereby declare the following to be a full, clear, and exact description of the same, sufficient to enable those skilled in the art to which my invention appertains to make use of it, reference being had to the accompanying drawings, forming part of this specification, in which—

Figure 1 is a side elevation of a chair having my improvement applied to it, and

Figure 2 a view in perspective of the upper portion of the same.

In this invention the head-rest is made vertically adjustable by means of a ratchet, and by the peculiar shape of the supporting-rod, the head-rest is thrown forward when the seat is extended or reclined, so as to support the head in a more comfortable position, and dispense with the necessity for a pillow or other support under the head.

Travellers on railroads, and others who have used adjustable head-rests for seats, have experienced much difficulty in properly adjusting them. In most cases they are fixed by means of a set-screw, or some device of that nature, operating in the rear of the seat, and obliging the occupant to get up and go round behind the seat to adjust his head-rest. One object of this invention is to obviate that difficulty. Another, and a still more important one is to provide a head-rest which can be thrown forward when the chair is placed in a reclining position, and thus be made to operate as a pillow to support the head a little higher than the rest of the person.

In the drawings, A is the body of the chair, and B is its back; C is the head-rest, and e is the rod or standard which supports it. The latter is bent, as shown in both drawings, the concave side being in front, and it is supported by ratchets *r r*, on the inner side of two posts or standards *R R*, in the back of the chair. The ratchets are made with deep teeth, which firmly hold the supporting-rod, the latter sliding between the two posts *R R*, and being provided with lateral arms *e' e'*, which engage with the ratchet. The head-rest can thus be adjusted by simply lifting it up, and throwing its upper end forward, so that the arms *e' e'* shall be brought behind the ratchet, where they will work up and down without engaging with its teeth. When raised or depressed as far as required, throw the head-rest back, and the arms *e' e'* will be brought forward in contact with the ratchet again, and will support the head-rest in that position. The head-rest will only be needed for use when the occupant of the chair desires to assume a reclining position, as shown in fig. 1. When such is the case, the bent supporting standard *e* will form its shape alone, bring the head-rest considerably forward, and cause it to serve as a raised pillow, which supports the head in an easy and comfortable position. When not raised, the head-rest fits down upon the back of the chair, forming apparently only a portion of the chair-back.

Having thus described my invention, what I claim as new, and desire to secure by Letters Patent, is—

The head-rest *C*, when made adjustable by means of a ratchet, *r r*, substantially as and for the purpose specified.

To the above specification of my invention, I have signed my hand, this twenty-ninth day of November, 1867.

J. R. CHILES.
